UNITED STATES PATENT OFFICE.

JACKSON G. CROWDES, OF BOSTON, MASSACHUSETTS.

ENGINE.

1,024,440.

Specification of Letters Patent. Patented Apr. 23, 1912.

Application filed November 25, 1910. Serial No. 594,005.

To all whom it may concern:

Be it known that I, JACKSON G. CROWDES, a citizen of the United States, residing at Boston, in the county of Suffolk and State 5 of Massachusetts, have invented certain new and useful Improvements in Engines, of which the following is a specification, reference being had to the accompanying drawings.

- 10 This invention relates to improvements in engines; and an object of this invention is to provide an engine which will be simple in construction and most efficient in operation.
- 15 In the drawings illustrating the principle of this invention and the best mode now known to me of applying that principle, Figure 1 is a central longitudinal section through so much of an engine as is necessary to illustrate this invention; Fig. 2 is a section on the line A—A of Fig. 1; Fig. 3 is a section on the line B—B of Fig. 1 but showing the parts in a different relative position; Fig. 4 is a section on the line 20 C—C of Fig. 1; Fig. 5 is a view similar to Fig. 1 but shows the exhaust ports centrally disposed and the pistons connected to different crank-shafts; Fig. 6 is a section on the line D—D of Fig. 5; and Fig. 7 is 25 a view similar to Figs. 1 and 5 but illustrates this invention as embodied in a single-acting engine.
- 30

The wall of the stationary guide cylinder *a* is chambered, as is shown at *a'* to provide the usual water-jacket and it is further formed near its middle with an inlet passage *b* the inner end of which opens into a semi-annular chamber *c*. The latter is in communication with the interior of the 35 guide-cylinder *a* through two series of radially-disposed ports, each of the series *d*, *e* being arranged on the arc of a semicircle (Fig. 2). At each end of the cylinder *a* and on the side thereof opposite from the 40 inlet passage *b* is formed a series *f* of radially-disposed exhaust ports which, as in the case of the admission ports *d*, *e*, are arranged on the arc of a semicircle (Fig. 4). Each series *f* of radially-disposed exhaust 45 ports lead from the inside of the stationary cylinder *a* to a semi-annular exhaust chamber *g* which communicates through an outlet passage *h* with the usual exhaust pipe (not shown).

50 Within the cylinder *a* is slidably fitted a hollow cylinder-piston *i* closed at its ends

and formed near its middle with a semi-circular series of inlet ports *j* and near each of its ends with a semicircular series of exhaust ports *k*. The ports *j*, *k* are radially disposed, as is clearly shown in Figs. 2 and 4. Connecting-rods *m* are pivotally fastened to the cylinder-piston *i* at one end thereof and also to the crank-disks *n* in the usual manner.

Within the cylinder-piston *i* is slidably fitted a piston *o* of the usual type. The piston *o* is mounted on the inner end of a piston-rod *p* which passes through a stuffing-box *q* and is fastened at its outer end to a crosshead *r*. By means of the rod *s* the latter is connected to the middle pair of crank-disks *n* at a point one hundred and eighty degrees from the points of connection of the rods *m*. Hence, as is clearly illustrated in Fig. 1, when the inner piston *o* is at the end of its travel in one direction, the outer or cylinder-piston *i* is at the end of the latter's travel in the opposite direction. In this position the inlet ports *d* of the cylinder proper *a* register with the inlet ports *j* of the cylinder-piston *i*; and the exhaust ports *k* of the latter are in register or "fair" with the exhaust ports *f* of the outer cylinder *a*. In case the engine is used as an explosion or internal combustion motor, the waste products of combustion will be driven out of the cylinder-piston *i* by the fuel which enters through the inlet ports *j*. Upon further movement of the crank-disks *n*, the parts will take the position shown in Fig. 3, in which the inlet and exhaust ports are closed and, as the outer piston *i* makes its forward stroke and the inner piston *o* its return stroke, the charge will be compressed in the space between the rear faces of the pistons *i*, *o*. Further movement of the latter in the same directions results in bringing the inlet ports *e* of the guide cylinder *a* into register with the inlet ports *j* of the cylinder-piston *i* and the exhaust ports of the same into register with the exhaust ports *f* of the guide cylinder at the front end thereof (left-hand end in Figs. 1 and 3). Suitable igniters *t* may be provided and the action of the same timed to produce an explosion at any desirable predetermined time, all in a manner well known to those skilled in this art. But, obviously, steam or other working fluid may be used to drive my new engine.

In Fig. 5 the exhaust ports f' , f'' of the guide cylinder a'' are located near the middle thereof and there is only a single exhaust outlet h' , with which the exhaust ports k' in the cylinder-piston i' are brought into communication through the exhaust ports f' , f'' and which leads only away from the engine. Further, in the engine illustrated in Fig. 5, the cylinder-piston 10 ton i' is connected by the rod m' with the crank disks n' , while the inner piston o' is connected by the rod p' with the crank disks n'' at the end of the engine opposite from the cranks n' . Thus, it will be seen that 15 the pistons may be arranged to drive separate mechanisms.

The engines shown in Figs. 1, 3 and 5 are all double-acting engines; but this invention may be readily embodied in a single-acting engine and Fig. 7 is designed to 20 illustrate an engine of the latter type which exemplifies this invention as thereto applied. The guide-cylinder a'' is formed with only one series e' of inlet or admission 25 ports and one series f of exhaust ports. The cylinder-piston i'' is open at one end to allow the pitman p'' , which is pivotally connected to the inner piston o'' , to pass. Of course, the connecting-rods m might 30 with perfect ease be linked to the rear face of the cylinder-piston i'' , instead of to its front face as shown in Fig. 7.

The use of radial ports, as hereinbefore described, enables me to obtain a large area 35 in the aggregate, while maintaining the area of the individual port small. Free admission and free exhaust result from this provision of a large total area.

For the same length of piston stroke, 40 greater power can be obtained from my new engine by the use of the two pistons one within the other and both movable. For the same length of piston stroke, the expansion is twice as great as in the ordinary engine, whereby an increase in efficiency is 45

realized. Since the pistons in producing compression move toward each other, the compression is greater in my new engine for the same piston travel (i. e., travel of one piston). It is to be observed that the cylinder-piston i serves really as a valve which controls admission and exhaust. 51

No special reversing mechanism is needed to reverse my new engine; it is necessary only to start the engine in the direction in 55 which it is to move, which may be done, of course, by turning the fly-wheel in the desired direction.

While I have herein shown my new engine adapted for use as a double-acting two-cycle internal combustion motor, yet it may be arranged without the exercise of more than the mechanical skill of the art to operate as a four-cycle engine. 60

I claim:

An engine having a pair of pistons one of which is hollow and closed at both its ends and within which is mounted the other of said pistons; a stationary guide cylinder formed a pair of inlet ports and a pair 70 of exhaust ports, said ports being substantially centrally arranged; a power-transmitting device connected to one end of said hollow piston; and a power-transmitting device which passes slidably through the opposite end of the latter and is connected to the other of said pistons slidably mounted therein; said hollow piston being formed with centrally-disposed inlet and exhaust 75 ports arranged to be brought into register respectively with the inlet and exhaust ports of said guide-cylinder. 80

In testimony whereof I hereunto set my hand in the presence of the two undersigned witnesses at Boston, Massachusetts, this 85 second day of November, 1910.

JACKSON G. CROWDES.
